Des. 2297

John H. Clark and John Rhinehardt, of Fort Wayne, Ind.,
Letters Patent No. 2297, Dated May 1, 1861.

Design for weather boarding.

The schedule referred to in the letters patent and covering part of the same.

Is all or how much it may concern.

Be it known that myself, H. Clark and
John Rhinehardt, of Fort Wayne, in the County of Allen, and State of
Indiana, have invented and improved Design for building, so
called, for Houses and other Buildings, and we do hereby declare

2

that the following and full patent description thereof, which will enable others skilled in the art to make and use the same, reference being had to the accompanying drawings forming a part of this specification.

The present invention relates to a new and improved design for a siding, so-called, or weather boarding for the exterior of houses, and other buildings, said design consisting in forming the various strips or boards comprising such siding or boarding of a bevel or tapering shape across its entire width, with the lower and thicker edges made with a suitable moulding to impart a finished and neat appearance to it.

There is also a complete of drawings of my improved design for a sliding or barrel siding.

Figure 1 shows a vertical section taken in the town of the same and,

Figure 2 shows a vertical section taken in the plane of the lines of Figure 1.

Oblique lines of reference indicate like parts.

A, A in the drawings represent a series of narrow strips or pieces of boards constituting a siding or weather boarding, which are secured to the frame of the house or other building by nailing or in any other proper manner, so as to overlap each other; each strip of the siding being made of a similar beveling or tapering shape across its entire width, and having its lower and thicker edges formed with a moulding, as plainly shown in Figure 2, thus producing a finished, and neat appearance thereto.

The claim is a new and improved design for a siding, as follows:

The design for a siding or weather boarding, having

bevelled and tapered with the drawings.

Witness,

Thomas A. Gandy
Jacob Kelt

{ John H. Clark.
